(57) **CLAIM**

The ornamental design for a door for electronic washing and drying machine, as shown and described.

DESCRIPTION

FIG. 1 is a front perspective view of the door for electronic washing and drying machine showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is a perspective view, with the door shown in use; and,

FIG. 10 is a perspective view, with the control panel shown in use.

The portions of FIG. 9 drawn in broken lines show environmental structure only and form no part of the claimed design.
